United States Patent Office

Des. 186,122
Patented Sept. 15, 1959

186,122

PLAYGROUND CLIMBING APPARATUS OR SIMILAR ARTICLE

Harold Zierhut, Van Nuys, Calif., assignor to Southern California Pipe & Steel Co., a corporation of California

Application August 27, 1958, Serial No. 52,398
Term of patent 14 years

(Cl. D34—5)

FIG. 1

FIG. 2

Figure 1 is a front perspective view of a playground climbing apparatus or similar article illustrating my new design; and,

Figure 2 is a rear perspective view thereof.

I claim:

The ornamental design for a playground climbing apparatus or similar article, substantially as shown.
